UNITED STATES PATENT OFFICE.

THEODORE ABTMAYER, OF WILKINSBURG, PENNSYLVANIA, ASSIGNOR TO WESTINGHOUSE ELECTRIC AND MANUFACTURING COMPANY, A CORPORATION OF PENNSYLVANIA.

PERCOLATING APPARATUS.

1,317,256.

Specification of Letters Patent. Patented Sept. 30, 1919.

Application filed April 14, 1913. Serial No. 760,917.

To all whom it may concern:

Be it known that I, THEODORE ABTMAYER, a citizen of the United States, and a resident of Wilkinsburg, in the county of Allegheny 5 and State of Pennsylvania, have invented a new and useful Improvement in Percolating Apparatus, of which the following is a specification.

My invention relates to electrically heated 10 apparatus, and it has special reference to liquid-percolating devices of the type adapted for immersion in liquid.

The object of my invention is to provide 15 a simple, inexpensive and reliable percolating device that is particularly adapted to aid the process of percolation.

Heretofore, percolating elements of the 20 above indicated character have embodied fountain tubes rigidly attached to the heater members, and the process of percolation has 25 been carried on solely by the difference of pressures obtaining in the various portions of the apparatus.

According to my invention, I provide a 25 means for aiding percolation that is additional to the usual means. The fountain tube is resiliently and loosely supported within the heater member and is adapted for reciprocating movement with respect thereto.

An upward movement is imparted to the 30 fountain tube by the expanding steam in the heating chamber, and its downward or return movement is cushioned by means of a spring that is associated with said tube 35 and said member. New liquid for heating is thereby forcibly taken in, and the heated fluid is aided in its upward projection.

In the accompanying drawing, the single 40 figure is a view in longitudinal section of a portion of a percolating element embodying my invention.

Referring to the drawing, a percolating 45 element 1 comprises a hollow base 2 inclosing an electric heater 3, and a fountain tube 4 resiliently supported in the well 5 in the upper side of the base 2.

The construction of the base 2 and the 50 heater 3 is well known in the art and need not be described. Any form of heating device may be used that has a base provided with a central well 5. The fountain tube 4 is suitably secured to a valve member 6 slidably and loosely fitting within an outer sleeve 7 that is supported coaxially with the 55 well 5 for guiding said valve member, and

a spiral spring 8 supports said tube and valve upon said sleeve. The valve member 6 comprises two cylindrical caps 9 and 10 secured to the lower end of the tube 4, and of slightly smaller diameter than the cylindrical guiding sleeve 7, which is joined to the base and constitutes an upward extension of the well 5. A side opening 11 in one of said caps and a side opening 12 in the tube 4 serve to admit liquid to the central well 5 where it is heated. It is understood that other suitable means for admitting liquid may be employed. One end of the spring 8 rests upon the upper end 13 of the sleeve 7, and a ring 14 is fastened to the tube 4 by a screw 15 and is provided with a circumferential disposed groove 16 in which the upper end of the spring 8 is disposed. The foregoing construction is adapted to permit resilient reciprocatory movement of the tube 4 and valve member 6 upwardly and downwardly in said well.

Assuming the apparatus to be in the position shown in the drawing, the operation is as follows: Liquid enters through the 80 space between the sleeve 7 and the valve 6, which space is shown somewhat enlarged for the sake of indicating that there is a space between these elements. The liquid then passes through the openings 11 and 12 in the cap member 9 and the tube 4, respectively, and drops to the bottom of the well 5, where it is heated and flashed into steam. The steam pressure acts on the valve member 6 as a piston, forcing said member upwardly, when more liquid is admitted through the opening 11. As soon as the steam pressure has momentarily decreased, the weight of the fountain tube and its usual attachments returns the valve member 90 6 and attached tube 4 to their original position, this downward movement being cushioned by the spring 8. The reciprocatory movement is continued as long as heat is furnished, thus aiding the process of percolation.

I do not wish to be restricted to the specific details and structure herein set forth, but desire that only such limitations shall be imposed as are indicated in the appended 105 claims.

I claim as my invention:

1. In a percolating element, the combination with an electric heater member comprising a base, of a fountain tube, and 110

resilient means for supporting the weight of the said tube upon said base.

2. A percolating device comprising a base having a liquid well in the upper side thereof, electric heating means disposed in said base adjacent said well, a fountain tube extending into said well, and a valve carried by the lower end of said tube and fitting in said well, said valve being freely operable during the normal operation of said device to control the flow of liquid into said well.

3. In a percolating element, the combination with an electric heater member, of a fountain tube associated therewith and reciprocable with respect thereto during the operation of the device, and resilient means for supporting the weight of the said tube.

4. In a percolating device, the combination with a base having a central well, of heating means carried by said base, a fountain tube supported within said well and adapted to move with respect thereto during the operation of the device.

5. In a percolating element, the combination with a base having a central well, of electric heating means carried by said base, a fountain tube supported within said well, and resilient means for supporting the weight of the said tube on said base.

6. In a percolating device, the combination with a heater member having a central well of less diameter than the said heater member, of a fountain tube, and means for so supporting said tube upon said member

so that the tube may reciprocate with respect to said member during the operation of the device.

7. In a percolating element, the combination with a heater member having a central well, of a fountain tube, means for so supporting said tube within said well that the tube may move up and down with respect to said member, and a member carried by the said fountain tube and fitting loosely within the said well.

8. A percolating device comprising a base having a liquid well in the upper side thereof, electric heating means disposed adjacent said well in said base, a fountain tube supported on said base and extending into said well, and a valve secured to the lower end of said tube and fitting within said well, said valve and tube being freely movable up and down in said well during the normal operation of said device to control the flow of liquid into said well.

9. A percolating device comprising a base having a liquid well in the upper side thereof, electric heating means disposed adjacent said well in said base, a fountain tube supported on said base and extending into said well, a valve secured to the lower end of said tube and fitting within said well, and means for resiliently supporting said valve and tube upon said base, whereby said valve and tube are freely movable up and down in said well during the normal operation of said device and control the flow of liquid into said well.

10. A percolating device comprising a hollow base having a liquid well in the upper side thereof, electric heating means disposed within said base adjacent said well, a fountain tube extending into said well, a valve secured to the lower end of said tube and fitting within said well, and a spring surrounding said tube and mounted upon the upper side of said base, said spring resiliently supporting said valve and tube whereby the same are freely movable up and down in said well during the normal operation of said device to control the flow of liquid into said well.

In testimony whereof I have hereunto subscribed my name this 3rd day of April, 1913.

THEODORE ABTMEYER.
